UNITED STATES PATENT OFFICE.

CARL C. WARNER AND ELMER D. PAUL, OF HAVERHILL, MASSACHUSETTS.

GRINDING-MACHINE.

1,255,962.

Specification of Letters Patent. Patented Feb. 12, 1918.

Application filed January 22, 1917. Serial No. 143,736.

To all whom it may concern:

Be it known that we, CARL C. WARNER and ELMER D. PAUL, citizens of the United States, residing at Haverhill, in the county of Essex and State of Massachusetts, have invented certain new and useful Improvements in Grinding-Machines; and we do declare the following to be a full, clear, and exact description of the invention, such as

10 will enable others skilled in the art to which it appertains to make and use the same.

Our invention relates to that class of machines designed for grinding irregular surfaces such as the cutting edges of knives 15 used in turning wooden heels for ladies' shoes, it being understood, however, that the application of the machine is not limited to this use.

The object of the invention is to provide 20 a machine of this class having improved means for properly presenting the surface to be ground to the grinding wheel so as to accurately impart the correct shape thereto and with this general object in view, the 25 invention resides in certain novel features of construction and unique combinations of parts to be hereinafter fully described and claimed, the descriptive matter being supplemented by the accompanying drawings 30 which constitute a part of this application and in which:

Figure 1 is a side elevation of the improved machine;

Fig. 2 is a longitudinal section thereof; 35 and

Figs. 3 and 4 are transverse sections on the planes of the lines 3—3 and 4—4 of Fig. 1.

In the drawings above briefly described, 40 the numeral 1 has reference to a horizontal base plate which may be secured upon a bench, upon a table 2 as shown in the drawings, or upon any other suitable support, said base carrying at one end a bearing 3 45 in whose upper end the horizontal shaft 4 of a suitable grinding wheel 5 is rotatably mounted. Formed integrally with the upper side of the base 1 and extending in a direction transverse of the shaft 4, is a dove- 50 tail track 6 receiving slidably thereon a carriage 7 which may be adjusted upon said track by hand and then locked against further movement by means of a set screw or the like 8.

55 Formed integrally with or rigidly secured in any other suitable manner to the car-

riage 7 is a second dove-tail track 9 which extends transversely of said carriage and receives slidably thereon a second carriage 10 which is thus movable parallel with the 60 axis of the grinding wheel 5. The under side of the carriage 10 is provided with a rack bar 11 received slidably in a slot 12 formed through the track 9, said bar meshing with a pinion 13 on the inner end of a 65 shaft 14 which projects rotatably and slidably through a bore 15 formed through the front portion of the track 6, said track being recessed at 15' to permit the pinion to move back and forth with the carriage 7 as 70 the latter is adjusted. The outer end of shaft 14 is provided with a hand wheel 16 by means of which it may be rotated to cause the pinion 13 and rack 11 to adjust the carriage 10 along the track 9.

75 Formed integrally with the carriage 10 or otherwise secured thereto and extending in the same direction as the track 6 is a third dove-tail track 17 upon which a third carriage 18 is slidably mounted, said carriage 80 having a vertically extending bracket 19 equipped with a vertical dove-tail track 20 receiving thereon a vertically moving carriage 21 which carries the work to be ground as will be described.

85 An arched matrix support 22 straddles the track 17 and rises from the carriage 7, said support having above the track 17 a pair of seats to receive matrices 23 and 24 which are held in place by screws or the like 25 as shown clearly in Figs. 2 and 3. Each matrix is provided with one irregular edge as will be clear from Fig. 3 and it is the function of these edges to move the carriage 18 along the track 17 and to shift the 95 carriage 21 along the track 20 against the tension of coiled springs 26 and 27 respectively, thus causing the work carried by the carriage 21 to move in the proper direction with respect to the wheel 5 for imparting the necessary formation to said work.

100 The carriage 18 is provided with a roller 28 traveling on the irregular edge of the matrix 23 while the corresponding edge of matrix 24 receives thereon a roller 29 on the lower end of carriage 21 so that these two carriages are moved in the required manner against the tension of their springs 26 and 27 respectively.

110 The springs in question may be mounted in any preferred manner but the inner ends thereof preferably bear against abutments

- 2
- 30 and 31 secured respectively to the outer end of the carriage 18 and the upper end of carriage 21, the outer ends of said springs being received slidably in tubular housings 5 32 and 33 secured respectively to the tracks 17 and 20, adjusting screws 34 and 35 being threaded through the outer ends of said housings for varying the tension of the springs 26 and 27 as occasion may require.
- 10 A bracket arm 36 is secured by screws or the like 37 to the carriage 21 and extends forwardly therefrom toward the grinding edge of the wheel 5, the outer end of said arm having a horizontally extending split bearing 38 receiving rotatably therein the arbor 39 of a work holding head 40, said head being preferably in the form of a flat metal block flanged at its ends at 41 and having suitable stop pins 42 and clamps 43 15 for securing blades or the like 44 in place. The arbor 39 as shown extends parallel with the shaft 4 of the grinding wheel 5 and may be locked against possible rotation by tightening the set screw 45 of the split bearing 25 38. Before tightening the screw, however, the arbor is temporarily locked against movement by means now to be described.
- A disk 46 is carried rigidly by the outer end of the bearing 38 and a screw 47 is 30 threaded into an opening in said disk, said screw passing through an arcuate slot 48 in a second disk 49 which contacts with the other and is rigidly mounted on the outer end of the arbor 39 so that after the head 40 35 has been properly adjusted, the parts may be locked in this position temporarily by tightening the screw 47, screw 45 being then tightened to lock the arbor against possible turning.
- 40 The head 40 is provided with two sets of stop pins 42 and clamps 43 in order that two blades such as 44 may be ground without varying the position of the matrices 23 and 24, thus insuring that the two blades be 45 of exactly the same contour. This is highly essential when grinding the blades of machines such as those used for turning heels, since it is necessary that both blades of the right as well as the left hand arbor be of the 50 exact shape.
- In operation, the blades to be ground are clamped upon the head 40 as depicted clearly in Fig. 2 and the carriage 7 is then fed forwardly the required amount to properly locate the uppermost of said blades with respect to the periphery of the grinding wheel 5. This having been done, the set screw 8 of the carriage 7 is locked and the set screws 34 and 35 are turned to place their respective 55 springs 26 and 27 under the required tension. The wheel 5 is now or previously set in motion and the carriage 10 is fed along the track 9 by means of the wheel 16 so that the blade being ground is moved back and forth across the wheel 5. During this move- 60
- ment, the springs 26 and 27 cause the rollers 28 and 29 to travel on the curved edges of the matrices 23 and 24. Thus the carriages 18 and 21 are properly shifted to so move the blade being ground as to cause the grinding wheel to impart the required shape thereto. After the uppermost blade has been ground, the head 40 is inverted by loosening the screws 45 and 47 so that the other blade may be sharpened while the 70 matrices 23 and 24 remain in the same positions in which they were placed while sharpening the first blade. This insures that the curvature of both blades shall be symmetrical.
- 80 After sharpening, say a pair of right hand blades in the manner above described, the matrices 23 and 24 may be reversed and the machine will then be in condition to sharpen, a pair of left hand blades, the operation being the same.
- 85 Screws 8' and 8'' similar to the screw 8 are by preference provided in order that the carriages 18 and 21 may be locked against movement so that the machine may be employed for grinding straight surfaces when required, it being understood that no matrices are then needed and consequently, the 90 springs 26 and 27 may be thrown out of action by loosening their respective screws 34 95 and 35.
- 95 From the foregoing, taken in connection with the accompanying drawings, it will be clear that although the invention is of rather simple and inexpensive nature, it will be highly efficient and durable. For these reasons, the construction shown and described constitutes the preferred form of the machine but it is to be understood that within the scope of the invention as claimed, 100 numerous changes may be made without sacrificing the principal advantages.
- 105 We claim:
1. A grinding machine comprising a grinding wheel, a horizontal track extending in a direction transverse of the axis of the wheel, a carriage movable along said track, a fixed matrix adjacent one end of said carriage and having an irregularly shaped face, said carriage having a shoe engaging said face, means for forcing said carriage along the track to retain the shoe and matrix in engagement, a vertical track carried by said carriage, a second carriage slidable along said vertical track and having at 110 one end a shoe, a second matrix engaged by said last named shoe, means for retaining said last named shoe in contact with said matrix, a work holder carried by said second carriage, and means permitting movement 115 of said first named track in a direction parallel with the axis of the wheel.
- 120 2. A grinding machine comprising a base, a grinding wheel supported above the same, a horizontal track on the upper side of said 125
- 130

- base extending in a direction at right angles to the axis of said wheel, a carriage slideable along said track, a second track carried by and extending transversely of said carriage, 5 a second carriage slideable along said second track and carrying a third track extending at right angles to the axis of the grinding wheel, a third carriage slideable along said third track, a matrix support carried by said first named carriage, a horizontal matrix carried by said matrix support and extending transversely of said third track, said third carriage having a shoe engaging said matrix, yielding means for normally moving said third carriage to position its shoe in contact with said matrix, a fourth and vertical track carried by said third carriage, a fourth and vertical carriage slideable along said fourth track and having at its lower 15 end a shoe, a second matrix carried by said matrix support and receiving said second shoe thereon, yielding means for so moving said fourth carriage as to retain its shoe in engagement with said second matrix, and a work holder carried by said fourth carriage for holding the work in proper relation to the grinding wheel.
3. A grinding machine comprising a grinding wheel, a work holder support in- 20
- cluding a horizontal bearing, said support being movable across said wheel, means for automatically moving said support in respect to the wheel for grinding irregular surfaces as it is moved in the first named manner, an arbor rotatably mounted in said bearing and having a head, means for locking said arbor against rotation, and means for clamping a pair of blades to the opposite sides of said head.
4. A grinding machine for irregular surfaces comprising a grinding wheel, a carriage movable in a direction parallel with the axis of said wheel and slideable toward and away from the latter, a matrix for automatically controlling the sliding movement of said carriage, an additional carriage carried by the other and slideable vertically, an additional matrix for controlling the sliding of said additional carriage, and a workholder carried by said additional carriage.

In testimony whereof we have hereunto set our hands in presence of two subscribing witnesses.
